SHOWER SPLASH GUARD

William E. Blitch, Charlotte, N.C., assignor to
The Webline Corporation

Filed Aug. 2, 1973, Ser. No. 385,184

Term of patent 14 years

Int. Cl. D23—02

U.S. Cl. D23—69

FIG. 1 is a perspective view of a shower splash guard showing my new design;

FIG. 2 is an enlarged perspective view thereof;

FIG. 3 is another enlarged perspective view taken from the side opposite that shown in FIG. 2; and

FIG. 4 is a further enlarged top plan view thereof.

The fragmentary broken line representation of a portion of a bathroom, a bathtub and a second shower splash guard in FIG. 1 is for purposes of illustration only.

I claim:

The ornamental design for a shower splash guard, substantially as shown and described.
